ANTENNA SYSTEM

Vernon D. Landon, Princeton, N. J., assignor to
Radio Corporation of America, a corporation of
Delaware.

Application July 30, 1949; Serial No. 107,792

8 Claims. (Cl. 250—33.65)

1

This invention relates to radio antennas, and particularly to the minimization of "feed-through," or direct transfer of radio frequency energy from one antenna to another nearby antenna.

This application is a continuation-in-part of my application for United States Patent Serial No. 665,403 filed April 27, 1946 and entitled "Antenna Systems," now abandoned.

In certain types of radar systems and radio altimeters, signals are radiated from one antenna and picked up by another after reflection from an object or surface whose distance is to be determined. It is generally necessary to prevent, insofar as is possible, feed-through directly from one antenna to the other without reflection from the object. At the same time, the antennas must be relatively close together, in some instances less than a wavelength apart.

Feed-through can be substantially neutralized, at any one frequency, by various known methods. However, in frequency modulation altimeters and the like, the frequency varies over an appreciable range, and neutralization of feed-through at only one frequency is ineffective.

The principal object of this invention is to provide improved methods of and means for reducing feed-through between adjacent antennas.

Another object is to provide, in a system of the described type, effective reduction of feed-through throughout a relatively wide frequency band rather than at only a single frequency.

The invention will be described with reference to the accompanying drawing, wherein:

Figure 1 is a plan view of an antenna structure embodying the invention;

Figure 2 is a section of Figure 1 along the line II—II of Figure 1; and

Figure 3 is a cross-sectional view of another embodiment of the invention.

The system illustrated is of the type employing series fed dipoles, as described and claimed in copending U. S. patent application, Serial No. 619,401, filed September 29, 1945 by O. M. Woodward, Jr. and entitled "Antenna Systems," now Patent No. 2,514,821 dated July 11, 1950. However, the utility of the present invention is not limited to this structure.

Referring now more particularly to Figures 1 and 2, the transmitting antenna 1 and the receiving antenna 3 are substantially identical, each comprising a pair of dipoles 5 and 7 and 5' and 7' respectively. The radiator arms of the dipole 5 are flat wing-shaped sheets, secured to and supported by the outer conductor of a co-

2

axial transmission line 9. A gap or slot 11 is provided in the outer conductor of the line 9, between the points of connection of the two radiators. The dipole 7 is like the dipole 5 and is similarly connected across a gap 13 in the outer conductor of the line 9, substantially one-half wavelength from the gap 11.

The upper end of the line 9 goes to a transmitter, not shown, and the transmission line is short-circuited at its lower end. This short-circuited end is remote from the point 13 a quarter line wavelength, and therefore, appears as an open-circuit at the point 13 so that the dipoles 7 are the only load seen by the transmission line 10 at the point 13. The inner conductor includes no gaps. A pan-like structure 15 acts as a reflector for the antennas 1 and 3, and supports the lines 9 and 9'.

A partition 17 is formed between the antennas 1 and 3. Rods 19 of polystyrene or similar insulating material are secured near the end of each wing of the dipole 5, extending down (see Figure 2) toward the bottom of the pan 15. An internally threaded bushing 21 in the bottom of the pan 20 supports an adjustable setscrew 23, whose upper end engages the lower end of the rod 19. Each wing of each dipole in both antennas 1 and 3 is provided with similar adjusting means. To allow adjustment both above and below the horizontal 25 plane in Figure 2, the wings may be bent downward initially, so that they act as flat springs urging the rods 19 into engagement with the screws 23.

The adjustment and operation of the system is 30 as follows:

Frequency modulated energy is supplied to the line 9 and radiated by the antenna 1. Energy picked up by the antenna 3 appears on the line 9' and is applied to a receiver, not shown. For 35 purposes of adjustment, the assembly as a whole is positioned so that substantially none of the radiation from the antenna 1 will strike any nearby reflecting objects. Any signal appearing on the line 9' is then caused by feed-through.

Each wing of the receiving dipoles 5' and 7' is 40 adjusted by means of its setscrew 23' to the position giving minimum output on the line 9'. It will be apparent that the dipole may be effectively tilted with respect to the reflector pan 45 by running one screw in and the other out, or may be bent up in a broad V shape or down in an inverted V by moving both screws in the same direction.

In practice it is found that both tilting and bending are generally required for minimum

feed-through. The reason for this is that the antennas 1 and 3 are so close to each other and to the reflector pan 15 that they act like loops, as well as dipoles, partly because substantial capacity currents flow from the tips of the radiators to the pan. The radiation from a loop is 90° out of phase with that from a dipole carrying the same current. Thus the coupling between the antennas 1 and 3 comprises two components vectorially at right angles to each other. 10 By tilting the receiving dipoles 5' and 7', pickup caused by one of these components can be minimized without greatly affecting the pickup caused by the other component. Similarly, bending up or down will minimize the other component.

Since the tilting and bending adjustments will interact on each other to some extent, it is necessary to make one adjustment, then the other, and repeat the first, and so on, to achieve minimum feed-through pickup by the antenna 3. This is followed by a similar sequence of adjustment of the transmitter antenna 1 to provide minimum field strength at the antenna 3.

Although substantially zero coupling can be obtained by critical adjustment of only one of the antennas 1 and 3, it is desirable to adjust both, thus superimposing the effects of the two null conditions. This makes the adjustments less critical, and affords substantial feed-through reduction over a relatively wide frequency band.

Referring now more particularly to Figure 3, an embodiment is illustrated only in cross sectional view which may comprise a transmitting antenna 1 and a receiving antenna 3 which are substantially identical and may be similar to those described in connection with Figure 1 having dipoles 5, 7 and 5' and 7' respectively, of which only 5 and 5' are visible in the view of Figure 3. The connections at the dipoles may be made in the transmission lines 9 and 9' in a manner similar to that of the embodiment of Figures 1 and 2. The same pan-like structure 15 may act as a reflector for the antennas 1 and 3 and support lines 9 and 9'. A partition 17 is formed as before between the antennas 1 and 3. A sheet 18 of dielectric material may be molded over the open face of the reflector to form a seal against the elements, thus protecting the antenna and permitting the transmission lines 9 and 9' to be pressurized or partially evacuated as desired.

An internally threaded metallic bushing 21 in the bottom of the pan may support adjustable metallic setscrews 23 which support on their upper end discs 30. The threaded portion of bushing 21 is preferably made sufficiently long and close fitting to provide certain metallic contact between the setscrews and the bushings 21 and thus with the pin 15.

The adjustment and operation of the system of Figure 3 is somewhat similar to that of Figure 1. The assembly as a whole is positioned so that substantially none of the radiation from antenna 1 strikes any reflecting objects. Any signal appearing on the line 9' is then caused by feed-through. Each setscrew 23 (and 23' for antenna 3) is adjusted to the position giving minimum output on the line 9'. It may be necessary to make the adjustments consecutively and repetitively from setscrew to setscrew.

The operation of both embodiments may be considered as being affected by the change of capacity between the dipole wings 5, 5' and the pan reflector 15. In the one case the distance between the antenna wings and the pan itself is

adjusted, each wing separately, and in the other case a similar adjustment is made if the discs 30, 30' may be considered as a portion of the pan reflector being brought closer to or further from the dipole wings.

It will be apparent that the invention affords simple and readily usable means for reducing feed-through over a relatively wide frequency band between adjacent antennas, particularly of the type employing disc or pan reflectors.

What I claim is:

1. In a radio antenna system including closely adjacent transmitting and receiving antennas, each including at least one doublet and a reflector, wherein both electric and magnetic coupling exists between said antennas, the method of minimizing feed-through comprising the steps of tilting one of said doublets as a whole with respect to said reflector to minimize one of said components of coupling, bending the arms of said doublet with respect to each other to minimize the other of said components of coupling, and similarly tilting and bending the other of said doublets to further reduce said respective components of coupling.

2. In a radio antenna system including a transmitting antenna and a receiving antenna closely adjacent thereto, each of said antennas including at least one doublet, and reflector means for said antennas, the method of minimizing transfer of energy between said antennas, comprising the steps of tilting each of said doublets as a whole to minimize one component of coupling between said antennas, and bending each of said doublets 35 in a broad V-shape to minimize a second component of coupling in quadrature phase with said first-mentioned component.

3. A radio antenna system for reflection-type altimeters and the like, including a transmitting antenna and a substantially identical receiving antenna in close proximity thereto, each of said antennas comprising a reflector in the form of a shallow pan and a plurality of doublets adjacent and approximately parallel to the bottom of said reflector, each of said doublets including two flat sheet radiator elements; means for adjusting and maintaining adjustment of said elements in respective angular positions with respect to said reflector to minimize feed-through between said antennas, comprising setscrews supported by said reflector adjacent each of said radiator elements and insulating rods connected to said elements and in engagement with said setscrews respectively.

55. 4. In a radio antenna system including apparatus for minimizing transfer of energy between a transmitting antenna and a receiving antenna closely adjacent thereto, each of said antennas including at least one doublet and reflector means for said antennas, the improvement comprising means for tilting each of said doublets as a whole to minimize one component of said coupling between said antennas, and means for distorting each of said doublets in a broad V-shape to minimize a second component of coupling in quadrature phase with said first-mentioned component.

5. A radio antenna system for reflection-type altimeters and the like, including a transmitting antenna and a substantially identical receiving antenna in close proximity thereto, each of said antennas comprising a reflector in the form of a shallow pan and a plurality of doublets adjacent and approximately parallel to the bottom of said reflector, each of said doublets including two

5

flat sheet radiator elements; means for adjusting and maintaining adjustment of said elements in respective angular positions with respect to said reflector to minimize feed-through between said antennas, comprising mechanical actuating means supported by said reflector adjacent each of said radiator elements, and insulating rods connected to said elements and in engagement with said mechanical actuating means respectively.

6. In a radio antenna system, apparatus for minimizing transfer of energy between a transmitting antenna and a receiving antenna closely adjacent thereto, each of said antennas including a doublet with two wings and a reflector for the doublet in front of which reflector said doublet is mounted, the improvement comprising separate mechanical means for each antenna wing extending from the reflector toward each wing and independent of the doublet mounting to adjust the effective distance of the end of each wing of the antenna doublets from the reflector.

7. In a radio antenna system, apparatus for minimizing transfer of energy between a transmitting antenna and a receiving antenna closely adjacent thereto, each of said antennas including a doublet having two wings and a reflector for the doublet in front of which said doublet is mounted, the improvement comprising separate mechanical means for each antenna wing extending from the reflector toward each wing and independent of the doublet mounting to adjust the capacitive relationship of each wing of the antenna doublet with the reflector.

6

8. A radio antenna system for reflection-type altimeters and the like, including a transmitting antenna and a substantially identical receiving antenna in close proximity thereto, each of said antennas comprising a reflector in the form of a shallow pan and a plurality of doublets each with two wings adjacent and approximately parallel to the bottom of said reflector, each of said doublets including two flat sheet radiator elements; means for adjusting and maintaining adjustment of said elements in respective angular positions with respect to said reflector to minimize feed-through between said antennas, comprising mechanical positioning means supported by said reflector adjacent at least some of said radiator elements, and adjustable capacitive means operatively disposed between said mechanical actuating means and said elements.
